METHOD FOR CASTING METALLIC ANNULI

Norman F. S. Russell and Frederick C. Langenberg, Edgewater Park, N. J., assignors to United States Pipe and Foundry Company, Burlington, N. J., a corporation of New Jersey

Application January 10, 1934, Serial No. 706,036

2 Claims. (Cl. 22—200)

Our invention relates to that method of casting metallic annuli such as pipes and, particularly, cast iron pipes, in molds formed of compacted non-conducting and refractory materials such as green sand molds or molds of a more permanent character designed for repeated use and made up of a mixture of materials which, on being baked at proper temperatures, will form a hard sintered mass. As heretofore practiced, a considerable amount of adherence occurs between the casting formed in such molds and portions of the mold surface, with the result that the surface of the casting is liable to be undesirably rough and with the further result that the mold surface is impaired and roughened and either entirely ineffective for subsequent use or so defectively effective as to produce in subsequent uses more defective pipes or annuli. It has been attempted to improve the character of the casting and increase the life of the mold by spraying the inside of the mold with a liquid vehicle charged with finely divided mold coating material so as to form a coating, which, after the drying of the vehicle, is hard and compact, but our experience is that coatings so applied are apt to rather increase than diminish the liability to form rough castings and defective molds. It has also been attempted to increase the smoothness of the casting and the durability of the mold by dusting, so to speak, the inside of the mold with finely divided mold coating material, generally, by shaking a bag of loose material containing the finely divided coating material over the mold but while this method of coating the mold does, in certain cases, produce an appreciable improvement in the smoothness of the casting, it cannot be relied upon to fill up the depressed surfaces which occur in all molds of the character in question or to prevent adherence between the portions of the mold substance proper and the casting which brings about roughness in the casting and injury to the mold.

The object of our invention is to provide certain improved steps in the application of a coating to molds of the kind in question and in the casting of the metal in contact with the coated mold which will result in a substantial elimination of the danger of adherence between the mold surface and the casting and in the production of an exceptionally smooth casting and its withdrawal from the mold with a minimum of injury to the mold and we have discovered that by progressively directing against contiguous portions of the mold a jet of a dry carrier gas charged with dry finely divided particles of mold

coating material that a coating of loosely adherent and loosely coherent particles of dry mold coating material can be built up upon the uneven surface of the mold which will fill up the depressed portions of the mold surface and form a smooth inner surface flush with or entirely submerging the more elevated portions of the mold and that by casting the molten metal in a so coated mold, little or no adherence takes place between the metal of the casting and the materials making up the mold proper and that such particles of the finely divided coating material as may adhere to the casting are, for the most part, easily brushed off so that the resultant casting is remarkably smooth and free from adherent material and that, at the same time, the avoidance of adherence between the materials of the mold proper and the casting permits the withdrawal of the casting from the mold with the least possible injury to the mold surface so that the useful life of the mold is materially increased, that is, it is made possible to cast a greater number of annuli in a mold coated in the manner which we have indicated than has heretofore been practicable.

The coating of finely divided dry coating material deposited on the mold by the jet of dry carrier gas is distinctly hydroscopic and where the atmosphere is charged with considerable water vapor there is a liability for the coating to lose its dry character by absorbing a considerable amount of water, the presence of which in the coating is highly detrimental as during the casting operation it is converted into steam which produces a rough and pitted surface on the casting and may even result in blow holes in the casting. It is necessary, therefore, that the casting should take place while the coating of finely divided dry coating material is sensibly dry and this is most effectively and satisfactorily insured by casting the metal in the prepared mold fairly promptly after the coating of the mold and before the coating has had time to become sensibly wet, although it is also practicable, in case the coating has become sensibly wet, to drive off the excess moisture by heat.

In our Patent Number 1,949,433, granted March 6, 1934, we have described and claimed our invention which consists, generally speaking, in depositing a coating of finely divided dry coating material upon the surface of an externally cooled metallic pipe mold by means of a jet of carrier gas charged with finely divided dry mold coating material directed progressively against contiguous areas of the mold

until the so treated mold surface is coated with a thin coating of the finely divided dry coating material which coating, for the best results, is also made up, to a considerable degree, of films 5 of the carrier gas adhering to the dry particles of coating material. The essential function of the so applied coating in the case of externally cooled metal molds is to effect such a retardation in heat transfer from the molten metal to the mold as will result in the formation of what 10 is generally known as a chill on the outer surface of the pipe or annulus but our method as described in our said former patent also lends itself very effectively to the formation of a pipe 15 casting which is not only free from chill but has also an entirely novel structure in that the resulting pipes are essentially made up of an outer zone consisting preponderantly of compacted interlaced dendrites of ferrite and/or 20 pearlite without unified directional tendency and an inner zone of graphitic formation free from dendritic formations, the resultant pipe being entirely machineable, highly resistant to impact 25 shocks and in other respects a decided improvement upon pipes as heretofore manufactured, particularly those made by the centrifugal process. This new pipe structure forms the subject matter of our co-pending application, Serial 30 Number 652,160.

In the case of pipes cast in molds made up of compacted, non-conducting and refractory materials, there is no liability for the formation 35 of a chill and the pipe structure throughout is graphitic but, as heretofore cast, such pipes were very liable to have a roughened exterior surface 40 of adhering particles or portions of the material making up the mold and the roughened surface of the pipe seriously impaired both the shock resisting capacity and tensile strength of 45 the casting and we have found that by coating the mold in the manner which we have described and casting the pipe in contact with the dry coating we not only increase the life of the mold but produce a pipe which is not only more attractive in appearance but is in fact a better 50 pipe although the internal structure of the casting would not seem to differ materially from that of pipes cast directly in contact with the mold surface.

In the coating by means of the charged jet 55 of carrier gas of sand molds or the like, it is practicable and indeed necessary to deposit upon the inner surface of the mold a considerably greater amount of the finely divided dry coating material per unit of area than was desirable or indeed practicable in the case of metal molds. This is, no doubt, to a large extent, true 60 because of the irregular surface to which the coating is applied and because our method of applying the coating progressively fills up the depressed portions of the mold in the course 65 of forming a smooth coating and it is also no doubt true that the irregular surface to which the coating is applied forms a better anchorage for the coating, rendering it less liable to flake off or to be displaced by the impact of the molten metal upon it. The quantity of coating material applied should be such as will fill up 70 and level off the depressed portions of the mold and come at least substantially flush with the higher portions and preferably even the highest 75 portions of the mold surface should be covered by the coating though not to any considerable depth.

While in the case of metal molds, the pres-

ence of occluded films of the carrier gas as a constituent portion of the coating plays a not unimportant part in the effectiveness of the coating and it is, therefore, desirable to pour the molten metal in the mold as soon as possible 80 after the coating is deposited upon it, in the case of sand molds or the like the presence of the occluded films of carrier gas in the make-up of the coating, while we believe it to be 85 advantageous, is by no means as important as in the case of the metal molds and it is, therefore, practicable to coat the molds considerably before the time at which the metal is 90 poured into them before casting and even to coat the mold before it is connected with the centrifugal machine in cases where the pipe is to be cast centrifugally.

While our invention is particularly useful as used in connection with the centrifugal casting of pipes or annuli, it is also usefully adapted for 95 pit casting in which case, of course, cores are used to define the inner surface of the pipe.

It will be understood from what we have said that our invention consists in applying to a pipe mold formed of compacted non-conducting refractory materials a coating of loosely adherent and loosely coherent particles of finely divided dry coating material by progressively directing against consecutively contiguous portions of the mold a jet of a dry carrier gas charged with 100 finely divided particles of dry coating material and then pouring molten metal in contact with the sensibly dry coating deposited upon the surface of the mold and preferably, though not exclusively, in carrying out these method steps in 105 connection with centrifugal casting of metallic annuli such as pipes.

With regard to the character of the coating material to be applied to the mold surface as described, pretty much any finely divided mold 110 coating material can be used which will not when exposed to the temperatures brought about by its contact with the molten metal, notably 115 adhere to the casting or to the materials of which the mold proper is made. Finely divided 120 ferro-silicon is well adapted for our uses as are also finely divided particles of sea coal, foundry 125 talc, graphite, powdered anthracite, silica flour.

In an application of the coating by means of a jet of carrier gas, it is necessary that the jet 130 should impart to the finely divided particles of dry coating material with which it is charged, sufficient energy to cause these particles to impact against the mold surface while at the same time the volume and velocity of the jet of carrier gas must be so regulated that the gas itself will 135 not impact against the mold surface with sufficient energy to blow away the particles of coating material deposited on the surface and built up into a coating upon the surface.

Where a stationary mold is used as in the pit casting of pipes, the molten metal is poured in the usual manner and where the annuli are cast centrifugally the metal may be poured into the mold in any convenient way. Thus, the metal 140 may be poured progressively through a runner into a relatively retractable mold as described, for example, in the de Lavaud Patent 1,398,008 of November 22, 1921, or a dump trough charged with molten metal may be introduced into the 145 mold and tilted to discharge its contents more or less simultaneously along the length of the mold as, for example, is described and shown in the patent to Millspaugh, 1,686,624 of October 9, 1928, or, again, the metal may be charged into 150

the spigot end of the mold which is preferably slightly tilted upward from the horizontal and permitted to distribute itself throughout the length of the mold by gravity as, for example, is described in the patent to Moore, 1,471,052 of October 16, 1923.

With regard to the application of the coating of finely divided dry coating material to the mold surface all that is necessary is that a jet of a dry carrier gas, charged with the finely divided dry particles of coating material should be so progressively directed against the portions of the mold to be coated as to progressively deposit upon contiguous areas of said surface a continuous coating of a finely divided dry coating material in sufficient amount to fill up and level off the depressed portions of the mold surface and produce a loosely adherent and loosely coherent smooth coating which will effectively prevent the metal being cast from entering the depressed portions of the mold surface and from impacting in the casting and making adherent therewith the more elevated portions of the mold surface. Many forms of carrier gas jet and of appliances for effecting such relative movement between the jet and the mold as may be necessary to effect a continuous coating of the mold may be used and we do not wish to be understood as confining ourselves to the use of any particular form of jet or to any of the appliances for effecting such relative shifting of the jet with respect to the mold as will bring the jet consecutively into operative relationship with the contiguous portions of the mold surface to be coated.

It will be understood that, where the cast pipe is to be withdrawn from the mold longitudinally, that the pipe should be formed without any beading on its spigot end if the advantage of our invention with regard to the repeated use of the mold is to be secured, as the withdrawal in this manner of a pipe having a beaded end would necessarily destroy the mold, although, even with pipes of this kind, the advantage of our invention in securing a smooth surface on the casting with consequent increase of strength would be fully availed of.

Where pipes are cast in green sand molds or the like and where it is desirable that such molds should be re-used, it is advisable that the cast pipe should be withdrawn from the mold vertically to diminish, as far as possible, the friction between the cast pipe and the mold surface but where the mold is of a semi-permanent character, it is quite practicable and generally most convenient to withdraw the cast pipe horizontally as the semi-permanent mold is quite capable of resisting the friction of the pipe.

As an aid to the understanding of our improved method we have illustrated in the drawings forming part of this specification apparatus well adapted for the practice of our improved method and, referring now to these drawings,

Figure 1 is a sectional elevation taken through the center line of the pipe mold of a centrifugal pipe casting apparatus adapted for the practice of my improved method, with certain parts shown in non-sectional elevation.

Figure 2 is a cross section on the line 2—2 of Fig. 1.

Figure 3 is a cross section on the line 3—3 of Fig. 1.

Figure 4 is an elevation taken through the center line of a pipe mold of an apparatus de-

signed to facilitate the coating of a sand lined mold preparatory to the insertion of the coated mold in a centrifugal pipe casting machine, certain parts of the mold supporting apparatus being shown in section.

Figure 5 is a fragmentary sectional view, taken on the line 5—5 of Fig. 4, illustrating an offsetting of the delivery nozzle with regard to the carrier gas conduit to which it is attached.

Figure 6 is a cross sectional view on the line 6—6 of Fig. 4.

Figure 7 is a cross sectional view on the line 7—7 of Fig. 4, and

Figure 8 is a diagrammatic and greatly enlarged sectional view of the inner surface of a sand lined mold to which a coating of finely divided dry coating material has been applied in accordance with our improved method.

Referring first to Figures 1 to 3 inclusive, A indicates a reciprocating carriage supported on suitable guide-ways or tracks indicated at A¹ by means of wheels A². A³, A³, indicate pedestals supported on the carriage. These pedestals support parallel shafts B, B, to which are attached mold supporting rolls, one pair of which, indicated at B¹, B¹, are formed with V-shaped surfaces, indicated at b¹, b¹, and one pair of which, indicated at B², B², are formed with cylindrical surfaces, as indicated at b², b². C, C, are yokes upon which are supported rollers, as indicated at C¹, C¹. These yokes are pivotally secured to one side of the carriage as indicated at C² and are detachably secured to the other side of the carriage, as indicated at C³, C³. D, D¹, indicate gear wheels secured to one end of the carriage and driven by a motor D² supported on the carriage. E indicates a cylinder and piston connected, as indicated at E¹, to reciprocate the carriage A. F indicates a stationary support for a pouring ladle indicated at F¹ and for a runner adapted to deliver molten metal to the mold and indicated at F². F³ indicates a cylinder and piston for tilting the ladle F¹. G indicates a conduit extending along and supported upon the runner F² and terminating in a jet nozzle G¹ adapted to deliver a jet of a carrier gas charged with particles of finely divided dry mold coating material outward against the surface of the pipe mold supported upon the mold A. The conduit G is connected with what we may call a gun indicated at G², into which is delivered through a pipe nozzle indicated at G³ a jet of a carrier gas from a reservoir of gas under pressure not shown, G⁴ indicating a pressure gauge and G⁵ a valve. H indicates a feeding device adapted to feed finely divided dry mold coating material to a hopper H¹ from which the mold coating material is fed into the gun G². The structure of the feeding apparatus is not shown in detail but, as diagrammatically indicated, is similar to that described in the patent to Hunt and Arnold, 1,939,703, of December 19, 1933, and the jet nozzle G¹, so far as indicated and as preferably constructed, is similar to that described in the application of Hunt and Arnold, Serial Number 640,257, filed October 29, 1932.

J indicates the shell or flask of a sand lined pipe mold, the sand lining being indicated at J¹. The shell J as indicated consists of a metal cylinder having a bell shaped end indicated at J², to the outer end of which is secured a flange ring indicated at J³ to which is bolted, as indicated at J⁴, a driving ring J⁵ having gear teeth J⁶ which, when the mold is in operative position in the machine, is engaged by the gear train D, 150

J indicates the shell or flask of a sand lined pipe mold, the sand lining being indicated at J¹. The shell J as indicated consists of a metal cylinder having a bell shaped end indicated at J², to the outer end of which is secured a flange ring indicated at J³ to which is bolted, as indicated at J⁴, a driving ring J⁵ having gear teeth J⁶ which, when the mold is in operative position in the machine, is engaged by the gear train D, 150

D¹. J⁷ is an annular track secured on the surface of the shell J and with a V shaped slot indicated at j⁷ which when the mold is in operative position is entered by the V b¹ of the rolls 5 B¹, B¹. Also secured upon the shell J is a flat faced annular track J⁸ which rests upon the cylindrical rollers B², B². As shown, the spigot end of the mold is formed with a radial flange J⁹ to which is bolted a ring K extending over 10 the end of the mold J¹ to a depth which will bring its inner edge flush with the inner edge of the pipe casting formed in the mold.

In Fig. 4, L is a laterally adjustable platform supported on guide-ways L¹ and adjusted thereon by means of screws L², L², which are gear connected as indicated at N, N, to a shaft N¹ which can be rotated as by means of a crank N². The platform supports pedestals L³, L³, which, in turn, support shafts L⁴, L⁴, to which 15 are secured mold supporting rollers, as indicated at L⁵, L⁵, and L⁶, L⁶. One of the shafts L⁴ is rotated through a chain belt L⁷ by a motor L⁸. J is a metal pipe mold flask lined with sand as indicated at J¹ and in other respects similar to 20 the mold shown in connection with Figures 1 to 3. M is a carriage supported on a track M¹ by means of the wheels indicated at M² and, as shown, reciprocated on said track by a motor M³, chain drive connected as indicated at M⁴ to a shaft or axle to which the supporting wheels 25 M² are attached. O, O, are pedestals supported on the carriage M and supporting a tapering tubular support indicated at O¹ which, in turn, supports the carrier gas tube indicated at G, to 30 the end of which is attached a nozzle G¹. The tube G is connected to the delivery end of a gun G² which, together with a feeding device for finely divided dry coating material indicated at H and the hopper H¹, are supported on the carriage M, the gun in this case having its nozzle G³ connected by a hose G⁶ to a source of air 35 under pressure, not shown.

In case the apparatus is to be used with molds of large diameter, it is advisable to connect the nozzle G¹ to the conduit G by means of an offsetting connection g as indicated in Fig. 5.

In Fig. 8, a portion of the sand mold J¹ is indicated and projecting portions of the sand are indicated at P with the depressed portions of the surface indicated at P¹ while we have indicated at Q the finely divided dry coating material filling up the depressions P¹ and forming a smooth surface slightly above the projecting portions P.

In the operation of the casting machine as shown in Figs. 1 to 3, the mold shell J lined with sand as indicated at J¹ is lowered into the casting machine having the gear J⁶ on its driving ring J⁵ engaged with the gearing D, D¹, and its circular tracks J⁷ and J⁸ resting on the rollers B¹, B¹ and B², B². The carriage A which during the insertion of the mold J¹ is at its greatest distance from the runner support F, is then moved toward the support and over the runner F² until the spout at the end of the runner registers with the bell end of the mold. Carrier gas is then admitted to the gun G² as by opening the cock G⁵ and finely divided dry coating material is fed to the gun by the feeding device H, H¹, with the effect of delivering a jet of carrier gas charged with dry finely divided mold coating material through the nozzle G¹ against the surface of the mold J¹ which previously has been set in rotation. Molten metal is fed to the runner F² from the ladle F¹ and as it is delivered

to the mold through the spout of the runner the carriage A is progressively retracted with the result that there is delivered upon the surface of the sand mold a coating of finely divided dry coating material upon which, as it is progressively formed, molten metal is progressively delivered so that at the completion of the outward motion of the carriage A the cast pipe is formed in the coated mold. The rate at which the finely divided dry coating material is delivered to the carrier gas in the gun and by the jet nozzle to the sand mold is such as to fill up the depressions P¹ in Fig. 8 and, in effect, to submerge the projecting portions P and form a smooth and approximately level surface, as indicated at Q in Fig. 8, with the result that the casting as formed upon the smooth surface of the finely divided dry coating material forming a loosely coherent and loosely adherent inner surface of the sand mold and a casting is formed 80 characterized by great surface smoothness and the absence of adherent portions of the sand mold and not only is the surface of the pipe 85 smoother than has heretofore been the case but, by reason of the smooth outer surface, the pipe 90 is materially stronger than is the case with 95 similar pipes having a more or less roughened exterior surface.

Where the sand mold is of a semi-permanent character and the casting formed without a bead upon its spigot end, the cast pipe can be 100 extracted from the mold while the mold is in the machine as by removing the core indicated at R and withdrawing the casting as is the common practice in machines of the general 105 character indicated in which an externally cooled metallic mold forms a permanent part of the machine after which the mold may be re-connected and a new casting formed as above described and so on until the mold requires 110 replacement but in cases in which a green sand mold or the like is used or in which a bead is 115 formed on the spigot end of the mold, the mold should be withdrawn from the casting after each casting operation and where no bead is 120 formed on the spigot end a casting may be withdrawn after the mold is removed from the machine under conditions which will have as little tendency as possible to injure the surface 125 of the sand mold so that it may be again coated and used.

Where a centrifugal casting machine of a different type from that illustrated in Figs. 1 to 3, is used, or when, for any reason, it is advisable that the sand mold should be coated 130 with a finely divided dry mold coating material before it is inserted in the casting machine, the coating may be applied to the sand mold in any convenient way, as, for example, is shown in Figs. 4 to 7. In this apparatus the circular shell 135 or flask J with the sand coating J¹, is placed on the supporting rolls L⁵, L⁵, and L⁶, L⁶, and set in rotation by the motor L⁸ and the chain belt L⁷ actuating the shaft L⁴ during the insertion of the mold in the machine. The carriage M is, 140 of course, retracted and, after the mold is in position and in rotation, an air jet is supplied to the gun G² through the nozzle G³ and finely divided dry coating material fed to the gun by the feeding apparatus indicated at H, H¹. As a 145 result, a jet of carrier gas charged with the dry finely divided coating material issues from the nozzle G¹ and the carriage M is then progressively moved toward the rotating mold by the motor M³ and the chain belt M⁴, with the result 150

that a helical band of dry coating material with overlapping edges is deposited upon the surface of the sand mold progressively until the entire surface has its depressed portions filled up and 5 a level surface formed by the coating material.

The lateral adjustment provided for the platform L by means of the threaded rods L² and the mechanism for actuating them is for the purpose of permitting an adjustment of the 10 mold position with regard to the jet nozzle which will bring about the best results in the deposition of the coating and permit the use of the apparatus for the coating of molds of quite different internal diameters. After the mold has 15 been properly coated, it is, of course, withdrawn from the coating apparatus and placed in position for the casting of a pipe where the casting is to be centrifugal in a centrifugal casting machine and where a bead cast pipe is to be formed 20 in proper position and connection with such appliances as are used for bead castings.

It must be understood that the mechanisms which we have illustrated and described are simply illustrative of mechanisms well adapted 25 for use in the operation of our improved method which is, in no sense, limited to the use of any particular mechanical device for carrying it into effect.

Having now described our invention, what we 30 claim as new and desire to secure by Letters Patent, is:

1. In the casting of metallic annuli in molds formed of compacted, non-conducting and refractory materials, the method steps which con-

sist in depositing upon the inner surface of the so constructed mold a loosely adherent and loosely coherent coating of finely divided dry coating material by progressively directing against consecutive portions of the mold to be coated a jet of a dry carrier gas charged with dry finely divided particles of mold coating material, then pouring molten metal in contact with the dry pulverulent coating of the mold to form an annulus and, after the metal has solidified, withdrawing the annular casting from the mold.

2. In the centrifugal casting of metallic annuli in flasks lined with compacted, non-conducting and refractory materials forming a mold surface adapted to permit the longitudinal withdrawal of an annular casting without fracture of the mold, the method steps which consist in depositing upon the inner surface of the mold a coating of loosely adherent and loosely coherent finely divided dry mold coating material by progressively directing against contiguous portions of the mold surface a jet of a dry carrier gas charged with finely divided dry particles of mold coating material, then pouring molten metal into the so coated mold and centrifugally 100 distributing said metal into the form of an annulus and, after the metal has set, withdrawing the annular casting from the lined mold flask in the direction parallel to the axis of the mold.
